UNITED STATES PATENT OFFICE.

EDWIN K. BROWNING, OF UTICA, NEW YORK.

MACHINE FOR CUTTING WOOD INTO SHREDS AND CRIMPING THEM FOR MATTRESS STUFFING, &c.

Specification of Letters Patent No. 8,217, dated July 15, 1851.

To all whom it may concern:

Be it known that I, EDWIN K. BROWNING, of the city of Utica, county of Oneida, and State of New York, have invented a new and useful machine and improvements for making from solid pieces of wood an article suitable for stuffing or filling cushions, mattresses, &c., to be used as a substitute for hair and other substances heretofore used for that purpose.

This machine and improvements are described as follows, reference being had to the annexed drawings of it and of its different parts making part of this specification.

15 Figure 1, is a front end view of the machine ready for operation, representing the splitters and plane drawn up ready to descend upon the edge of the board from which the split shaving is to be taken, also showing the position of the balance wheel I and of the loose and driving pulleys K K', and showing on the side of the machine the cam and eccentric wheel L, the feeding rod M and primary feeding wheel O and on the back of the machine, three geared feeding wheels Q, R, R' and the feeding block T.

20 Fig. 2, is a side view of the machine representing that part of the frame which contains the board to be operated upon and the block T to drive it up to the splitters and plane, this is called the feeding block, this figure also represents the shaft P, which connects the primary feeding wheel O with the first geared wheel Q on the back of the machine, and it also represents the two screws S S' which are worked by two geared 25 wheels which are most fully represented in Fig. 3.

30 Fig. 3 is a representation of the lower part of the back of the frame of the machine showing two geared wheels R, R' on the feeding screws S, S', and their connection through the intermediate geared wheel Q with the primary feeding wheel O and feeding rod M, and also showing the feeding 35 block T to which are attached the screws S, S'. The cam and eccentric wheel L, the rod M, the wheel O, the geared wheels Q, R, R', the screws S, S, and the block T are all contrived and adjusted to bring the board up to the splitters and plane at the proper moment and the proper distance, hence they are termed feeding.

40 Fig. 4 is the cam and eccentric wheel L which first forces down the feeding rod M

and afterward permits it to spring up into the shoulder n, whereby the primary feeding wheel O is caused to move slightly, which motion is communicated to the geared wheels Q, R, R', which turn the screws S, S', and thus the feeding block T forces forward the board to be split and planed, a distance equal to the thickness of the next cutting.

45 Fig. 5 is a side view of the frame or stock E containing the splitters a and the planing iron d.

Fig. 6 is a view of the bottom of the stock E representing the points of the splitters a, the edge of the plane iron and the holder i to prevent strips from passing out of the 50 crimping box in between the edge of the plane and the edge of the board which is to be split and planed.

Fig. 7 is a top view of the stock E showing the ends of the splitters and of the plane 55 iron and the top or lid of the crimping box f.

The machine and all its parts, may be made of iron, steel, or any other suitable material of suitable size and strength, and of any number of splitters, depending upon the 60 length and breadth of the edge of the board to be split and planed.

65 The nature of my invention and improvements consists in certain new and useful combinations and arrangements of mechanical devices, by which the edge of a board is split into a great number of flat thin strips by means of splitters arranged side by side, which strips are immediately taken off by a plane following, and crimped in a crimping 70 box and from thence discharged by their own pressure in a state fit to be used as a stuffing for mattresses, cushions and other articles, the strips being flat, and can be 75 taken from the hardest of wood and are 80 more thin and elastic than the round shred or shaving and may be made narrow or 85 wide as desired.

90 Similar letters are used in the several figures to designate the same parts.

95 The frame of the machine, see Fig. 1, letter A, is upright and is placed upon a stand A', raised sufficiently from the floor to prevent the stuffing from accumulating around the splitters and plane. To the front 100 edge of this upright frame A, Fig. 1, are fastened two ways B, B, on which the cross head C and carriage D work, on the lower side of this cross head and forming part of it, is a cast iron carriage D on to which is 105 110

fastened the stock E, this stock E is well represented in Figs. 5, 6 and 7, and to these I will now refer. In this stock E are the splitters *a*, the number and size of which depend upon the breadth of the edge of the board to be split and the size of the stuff desired. The ends of these splitters *a* and the place for their insertion in the stock E are seen in Figs. 5 and 7 and the points of 5 the splitters *a* are seen projecting through the bottom of the frame in Fig. 6, these splitters are made of separate pieces of steel, blunt at one end and sharpened at the other. A separate aperture is made in stock E for 10 them in which they are fastened by the screw *e* so that they can be taken out at pleasure to be sharpened or replaced by others, without destroying the end of the machine. Immediately behind these splitters (see Fig. 5) is placed the planing iron *d* which is a simple planing iron, and its position and firmness are regulated by the screw *e*. Directly in front of this planing iron (see Fig. 7) is an opening in frame E 15 provided with a lid *f* hung on centers *g*, *g*, this lid is made sufficiently heavy to retain the strips which are cut from the edge of the board until it is full, thus giving that degree of resistance or pressure on each strip 20 so that it is curled or crimped by the weight of the lid as fast and as soon as it is cut off from the board, to force all these strips into this box, two guards are placed on each side of the edge of the plane *h* *h* (see Fig. 6) and 25 to prevent any strips from forcing their way back between the edge of the plane and the edge of the board while the plane is passing up, at which time the board is not quite against the edge of the plane, a holder is 30 provided which is marked *i* and has an arm marked *j* the holder lies directly in front of the plaining iron and while the plane is taking off the strip from the edge of the board, does not touch it, but when the plane 35 is pressing up and back preparatory to another cutting, this cut off is thrown up and on to the edge of the planing iron, thus cutting off all opening between the edge of the planing iron and frame, until the splitters 40 and planing iron begin to descend and then it is thrown down and off the plane by means of two pieces which are seen in Fig. 45 1, and to which figure we will now refer for the residue of the description, thus in Fig. 50 50 55 60 65 70 75 80 85 90 95 100 105 110 115 120 125 130

1 will be seen a long strip of iron passing from the upper part of the carriage to the lower part of the carriage; this is marked *k*, and is provided with two notches *k*¹ *k*² to hold the arm *j* of the cut off *i*. On the left side of the frame, are two projecting points or pins marked *F*¹, *F*².

We will now suppose the carriage, with the frame, splitters and plane up and ready to descend to take off that part of the edge 65 of the board which shall be split by the pre-

ceding splitter, at this period, the holder *i* with the arm *j* is thrown down and off the plane, now the carriage and plane descend, and just as they reach the extreme point to which they descend, the arm *j* of holder *i* comes in contact with the projecting point *F*¹ and is thrown up and on to the planing iron, and is held firmly in that position by the catch *k*¹ on the iron *k* and there retained while the carriage, splitters and plane ascend, carrying with them arm *j*, but just as they reach the extreme point of ascent, the arm *j* comes in contact with the projecting point or pin *F*² and is thrown down and off the planing iron, the arm *j* being thrown into notch *k*² and held firmly there until it descends as far as the projecting point *F*² when it is again drawn back on to the plane and into notch *k*¹. To the cross head C on the upper side is attached the pitman G which is moved by the crank H at one end of which is attached the balance wheel I and at the other end on shaft J, is the driving pulley K, and loose pulley K'; it is from this driving pulley that motion is 70 75 80 85 90 95 100 105 110 115 120 125 130 communicated to the entire machine; between the driving pulley K and the frame A and on the same shaft J is the cam and eccentric wheel L—this is keyed to the shaft J, and revolves with it—directly under this cam and eccentric wheel and pressing against it, is the rod M; this rod is forced up against the cam wheel by a spiral spring, which is represented in the annexed drawing by the letter *m*; the cam to which we have referred, is represented detached from the shaft by Fig. 4; it will be observed that this cam wheel is also an eccentric having its greatest diameter just at the shoulder *n*; when the cam and rod are both in place on the starting of the machine, the end of the rod is up on the shoulder *n*—as the splitters and plane pass down over the edge of the board, the cam revolves gradually bringing its greatest diameter to bear upon the end of the rod and then pushing it down so that just before the splitters and plane reach the extreme point of their ascent, the rod is thrust down as far as the eccentric cam wheel will drive it. Now on looking at the lower end of the feeding rod M, it will be seen that it has attached to it, friction jaws N, which hold the primary feeding wheel O, these jaws, it will be seen, open as the rod M is thrust down, but close tightly when the rod is elevated, so that when the eccentric cam wheel L, thrusts down the rod M, the jaws open and pass down and take hold of the circumference of wheel O lower down, at this moment the splitters and plane have reached the extreme point of their ascent, the cam wheel has revolved so far that the rod has reached the shoulder *n*, and when the spring *m* on the rod forces it up into the shoulder, the upward motion of the rod

causes the jaws N to close tightly on to wheel O and make that wheel move a distance equal to the depth of the shoulder *n* in the cam and eccentric wheel L. Now 5 wheel O is fastened to the shaft P which is seen most clearly in Fig. 2, which is also the shaft of the geared, intermediate feeding wheel Q which is seen best in Fig. 3, and the wheel Q gears into two geared wheels R, R' 10 both of which revolve on and work forward and backward the screws S, S', these screws are fastened to the top and bottom of the back of the feeding block T, to this feeding block, the board to be split and planed is 15 fastened edgewise by means of two arms and screws *t* *t'*, the bottom of the feeding blocks moves forward or backward in a groove at the bottom of the frame marked U, see Figs. 1 and 2, while the top moves 20 in the space formed by the frame A as seen in Fig. 3, this feeding block moves forward until the board is all cut into materials for stuffing and then moves backward to receive another board. Now when motion is given 25 to wheel O, see Fig. 3, it is communicated by shaft P to wheel Q and thence to the two wheels R, R', which turns the screws S, S' and thus push forward the feeding block T and with it the board, a distance 30 equal to the thickness of the next split to be taken off. Inasmuch as it would dull the splitters and plane to have the board fed up upon them while they are being drawn up, the machine is so arranged, that the top 35 of rod M does not reach the shoulder of the cam wheel L until both plane and splitters are drawn up high enough to cleave the board—then the rod reaches the shoulder *n*, and by the force of springs *m* is forced 40 upward closing the jaws N on to wheel O and causing the revolution which we have just described as causing the feeding screws to push forward the feeding block T. Wheel O is preferred to a ratchet wheel, because if 45 anything should occur by means of which

the splitters and plane iron should not operate; the unusual amount of pressure back through the screws and geared wheels to wheel O would cause the jaws N to give or slip and thus prevent breakage. 50

The ordinary size of the split shaving is about one sixteenth of an inch wide and one thirty second thick and is crimped, not curled; and the hardest of wood can be split and cut in this way, it makes a different article from anything heretofore used, and much more light, elastic and durable—the crimping is done as soon and as fast as the strip leaves the timber or board from which it is taken, by pressure against the throat of 60 the plane, this pressure may be caused by various ways—as placing a bar across the throat, but the weighted, movable lid *f*, is preferred because it has sufficient weight to crimp and at the same time does not choke 65 up and is self-discharging.

I do not claim the combination of fluted cutters with smooth cutters for the purpose of making this article, nor do I claim or use the fluted cutters at all, nor do I cut the 70 wood into round threads, but into flat strips which are light and more elastic. Nor do I claim the arrangement of fluted and smooth cutters in the plane stock, nor the apparatus for holding timber and feeding it up to the 75 plane as it has heretofore been used and patented, but

What I claim as my invention and desire to secure by Letters Patent, is—

The use of the splitters with the plane 80 iron, and the holder *i*, and the movable weighted lid *f* or anything which is substantially the same combined and arranged in the plane stock E for the purpose of producing the article herein described.

EDWIN K. BROWNING.
